HOLD-DOWN DEVICE

Nadzerin Gentiline, Kingsford, Mich.

Application January 4, 1957, Serial No. 632,537

5 Claims. (Cl. 248—361)

This invention relates to fastening means, and more particularly to a device for releasably anchoring an object to a support.

A main object of the invention is to provide a novel and improved releasable hold-down device which is simple in construction, which is easy to operate, and which provides a yieldable but secure anchoring effect on the object with which it is engaged.

A further object of the invention is to provide an improved hold-down device for fastening a boat or similar object onto a trailer or other supporting means, the hold-down device being inexpensive to fabricate, being rugged in construction, being arranged so that it is not subject to accidental unlocking, being yieldable to assist in absorbing road shocks and thereby minimizing damage to the boat anchored thereby, and being operable by simple manual movements.

Further objects and advantages of the invention will become apparent from the following description and claims, and from the accompanying drawings, wherein:

Figure 1 is a fragmentary perspective view of a portion of a boat trailer and a boat anchored on the trailer by means of an improved hold-down device according to the present invention.

Figure 2 is an enlarged vertical cross sectional view taken on the line 2—2 of Figure 1.

Figure 3 is an enlarged elevational view of the lower portion of the hold-down device employed in Figures 1 and 2.

Figure 4 is a perspective view, to a reduced scale, showing the hold-down device of the present invention provided with extension means to reduce the anchoring force exerted thereby, or to elongate the same, in accordance with the nature of the boat with which the device is to be employed.

Referring to the drawings, and more particularly to Figures 1, 2 and 3, 11 designates a support, for example, the frame of a boat trailer shaped to receive a boat 12 thereon. The frame 11 has secured to the side thereof a bracket member 13 which is formed with an outwardly projecting vertical flange 14 extending substantially at right angles to the main body of the plate-like bracket member 13.

The flange 14 has horizontally extending top and bottom edges and is formed in its bottom edge with a rectangular notch 15. Designated at 16 is a generally L-shaped arm pivoted at its inner end to the upper forward corner of the bracket plate 13, as shown at 17, the arm 16 being spaced from the bracket plate so as to be in the same longitudinal vertical plane as the notch 15, for example, by the use of a spacing washer 18 between the arm and the plate 13. As shown in Figures 1, 3 and 4, the outer portion of arm 16, designated at 19, is arranged so that the intermediate portion thereof will be received in the notch 15 when the arm is in its rearwardly extending position, shown in Figures 1, 3 and 4.

Designated at 20 is a link bar which is pivoted to the arm 16 between the flange 14 and the pivotal con-

2

nnection 17 of the arm, as shown at 20, preferably between the flange 14 and the bend in the arm 16 when the arm is in the position thereof shown in Figure 1. One end of a coiled spring 21 is connected to the top end of the link bar 20. The opposite end of the spring 21 is formed with a hook 22 which is engaged with the outwardly projecting hook element 23 of a generally U-shaped anchoring bracket 24 adapted to engage over the top edge of the side wall of the boat 12 in the manner clearly illustrated in Figures 1 and 2.

The arm 19 may be swung counterclockwise from its position shown in Figure 1 and shown in full line view in Figure 3, to the dotted view position thereof shown in Figure 3, the pivotal connection 17 being so located that in this dotted view position the major portion of rim 19 and the portion of link bar 20 connected thereto are above the top edge of flange 14, whereby the tension on the spring 21 is released. This is the position of arm 16 when the device is being first applied to the top edge of the side wall of a boat 12 to be anchored to the trailer supporting frame 11. Thus, the U-shaped bracket member 24 is engaged over the top edge of the side wall 12 of the boat, and the arm 16 is then rotated clockwise from its dotted view position of Figure 3 to the full line position thereof, whereby the link bar 20 is rotated clockwise past the dead center position thereof with respect to the pivot pin 17, developing substantial tension in the spring 21 and allowing the outer portion 19 of the arm 16 to engage in the notch 15. The tension in the spring 21 maintains the top edge of the arm 16 engaged in the notch 15 and the flange 14 supports the arm 16 against the force of the spring.

As will be apparent from Figures 1 and 3, the outer portion of the arm 16 projects rearwardly and cannot be easily rotated by contact with objects on the road while the trailer is being moved forwardly, whereby accidental release of the hold-down device is avoided.

If it should be desired to reduce the tension exerted on the anchored object by the spring 21, or to extend the hold-down device to engage a larger boat or other object than originally contemplated, an extension chain 25 may be connected between the spring hook 22 and the bracket hook 23, as shown in Figure 4.

While a specific embodiment of an improved hold-down device for a boat trailer or for a similar support has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a support, a hold-down device comprising an arm pivoted at one end to the support, an outwardly projecting vertical plate-like abutment member on the support adjacent the pivotal connection of the arm, said abutment member having a top edge and having a bottom edge and being engageable at its bottom edge by the top edge of the arm, an upwardly extending link bar connected at its bottom edge to the arm between said abutment member and said pivotal connection, said pivotal connection being so located that said arm and the portion of the link bar connected thereto are at times rotatable away from said bottom edge to a position wherein the major portion of the arm and said portion of the link bar are above the top edge of the abutment member, a coiled spring connected to said link member, and hook means connected to the end of said spring and being engageable with an object to be anchored on the support.
2. In a support, a hold-down device comprising an arm pivoted at one end to the support, an outwardly

projecting vertical abutment flange on the support adjacent the pivotal connection of the arm, said abutment member having a top edge and a bottom edge and being engageable at its bottom edge by the top edge of the arm, the bottom edge of the flange being formed with a notch to receive the top edge of the arm, an upwardly extending link bar connected at its bottom end to the arm between said abutment flange and said pivotal connection, said pivotal connection being so located that said arm and the portion of the link bar connected thereto are at times rotatable away from said bottom edge to a position wherein the major portion of the arm and said portion of the link bar are above the top edge of the abutment member, a coiled spring connected to said link member, and hook means connected to the end of said spring and being engageable with an object to be anchored on the support.

3. In a support, a hold-down device comprising an arm pivoted at one end to the support, an outwardly projecting vertical abutment flange on the support adjacent the pivotal connection of the arm said abutment flange having a horizontal top edge and having a horizontal bottom edge spaced a substantial distance below said pivotal connection, said bottom edge being engageable by the top edge of the arm, said bottom edge being formed with a notch to receive the top edge of said arm, an upwardly extending link bar connected to the arm between said abutment flange and said pivotal connection, said pivotal connection being so located that said arm and the portion of the link bar connected thereto are at times rotatable away from said bottom edge to a position wherein the major portion of the arm and said portion of the link bar are above the top edge of the abutment member, a coiled spring connected to said link member, and hook means connected to the end of said spring and being engageable with an object to be anchored on the support.

4. In a support, a hold-down device comprising a generally L-shaped arm pivoted at one end to the support, an outwardly projecting vertical abutment flange on the support adjacent the pivotal connection of the arm said abutment flange having a horizontal top edge and having a horizontal bottom edge spaced a substantial distance below said pivotal connection, said bottom edge being formed with a notch to receive the top edge of the arm 40

and being spaced a substantial distance below said pivotal connection, an upwardly extending link bar connected to the arm between said abutment flange and said pivotal connection, said pivotal connection being so located that 5 said arm and the portion of the link bar connected thereto are at times rotatable away from said bottom edge to a position wherein the major portion of the arm and said portion of the link bar are above the top edge of the abutment member, a coiled spring connected to said link member, and hook means connected to the end of said spring and being engageable with an object to be anchored on the support.

5. In a support, a hold-down device comprising a generally L-shaped arm pivoted at its inner end to the support, an outwardly projecting vertical abutment flange on the support adjacent the pivotal connection of the arm said abutment flange having a horizontal top edge and having a horizontal bottom edge spaced a substantial distance below said pivotal connection, said bottom edge being engageable by the top edge of the outer portion of the arm, the bottom edge of the flange being formed with a notch to receive the top edge of the outer portion of the arm, an upwardly extending link bar connected to the arm between said abutment flange and said pivotal connection, said pivotal connection being so located that 15 said arm and the portion of the link bar connected thereto are at times rotatable away from said bottom edge to a position wherein the major portion of the arm and said portion of the link bar are above the top edge of the abutment member, a coiled spring connected to said link member, and hook means connected to the end of said spring and being engageable with an object to be anchored on the support.
